UNITED STATES PATENT OFFICE

FREDERICK C. HERSEE, OF BELMONT, MASSACHUSETTS

ELECTRIC SWITCH SOCKET

Application filed January 31, 1930. Serial No. 424,890.

This invention relates to switch sockets for electric lamps and is designed preferably, but not exclusively, for use in connection with lighting systems for automobiles. The invention aims to provide an improved switching portion for establishing and dis-establishing the lighting circuit at will, including control means located outside of the socket for manually operating the switch.

10 The invention will best be understood from a description of a preferred embodiment thereof illustrated in the accompanying drawings, wherein

15 Figure 1 is a side elevation of an electric lamp switch socket containing my improvement, a portion of the socket mounting or automobile body, which serves as a terminal for grounding the circuit being shown in section;

20 Fig. 2 a longitudinal vertical section of the parts shown in Fig. 1;

25 Figs. 3, 4 and 5 cross sectional views on the lines 3—3, 4—4 and 5—5, of Fig. 2, showing respectively face views of the front and rear contact springs of the switch portion, and the inner end of the insulation plug and terminal mounted in the rear end of the socket.

The cylindrical metal casing 10 is adapted 30 to receive at one end a lamp bulb 11 removably secured therein by suitable interlocking means, such as the usual bayonet joints comprising the slots 12 arranged on opposite sides of the casing rim and the corresponding 35 studs 13 provided on the lamp base 14. In the opposite end of the casing is suitably secured a permanent terminal plug 15 of insulation material. This plug has a bore therethrough parallel with but eccentric to 40 the axis of the plug to receive a metallic socket or terminal member 16, into which the bared end, forming a terminal 17, of an insulated conductor 18 is inserted and detachably held by suitable means, such as an adjustable set screw 19. I have illustrated only

one of the circuit conductors, it being designed in the present embodiment to ground the opposite or return side of the circuit on the frame work of the motor vehicle, a part of which is indicated at 20. The socket or terminal member 16 is thus similarly disposed eccentric to and parallel with the axis of the casing 10, its forward end being exposed within the casing and flush with the inner face of the plug 15.

Within the casing in the space intervening the lamp and the terminal plug 15 is a rotatable switch portion including an insulation block 21, which is operatively controlled exteriorly of the casing by suitable means such as the switch lever 22 screwed or otherwise removably secured at one end in a corresponding threaded opening in the block 21 and extending through a suitable slot or opening 23 in the casing wall.

Carried on the rear face of the block 21, and disposed within the space intervening the block and the plug 15, is a contact spring 24 for yieldable engagement with the terminal member 16. Said contact spring being 70 preferably terminally provided with a lateral extension member 25 presenting a contact point which is eccentric to the axis of the block 21 for engaging the inner face of the terminal member 16 during circuit operation, while arranged on the opposite face of the block 21 and disposed within the space intervening the block and the lamp base 14 is another contact spring 26, for constant engagement with the usual fixed contact 27 centrally 75 provided on the rear end of the lamp. Said contact springs 24, 26 are detachably secured to the block 21 by suitable means and electrically connected together to provide an ample uninterrupted path offering the minimum of resistance to the circuit. The contact springs 24, 26 are preferably formed 80 out of a single piece of spring metal strip 28 of suitable conductivity and cross sectional proportions to carry the current without any 85

appreciable heating, whereby the spring qualities in the metal are not affected, thus avoiding the usual deterioration of the metal and loss of tensional strength commonly experienced when fine wire coil springs or other similarly objectionable devices are employed to maintain engagement between the contact points and corresponding terminals or other parts of the circuit.

10. In the present embodiment of my invention, the body of the strip 28, out of which the contact springs are preferably formed, is disposed centrally within a transverse recess 29 provided on the margin of the block 21 opposite the lever 22, the ends of the strip projecting beyond the block on either side being first bent at right angles to grip in clamping engagement the corresponding adjacent faces of the block 21, each end being then bent in the reverse direction, forming U-shaped structures presenting different arcs of curvature adapted to the prevailing space conditions and respectively engaging the terminal member 16 and the lamp contact 27.

15. To avoid accidental displacement in any direction of the strip 28 with the contact springs 24, 26 from their given positions with respect to the block 21, the clamping engagement of the yoke-like structure thus formed to permit a slip-on connection may be supplemented by additional means, if desired, which may be either positive or non-positive in character; but preferably of such construction that the easy removability of these parts is not impaired. Such supplemental securing means is herein illustrated by the provision of extension members 30, 30 on the opposing sides of the contact springs 24, 26, and preferably raised out of the material of which the springs are constructed, to register with corresponding openings provided in the faces of the block 21, herein shown at the opposite ends of a transverse bore 31 extending through the axis of the block 21, said members 30 being held in respective registering position by the gripping action of the contact springs. It will be observed that by the foregoing construction the entire contact spring assembly may be readily removed and replaced at will in one piece without the aid of any tools or the removal of fixed parts if, by reason of wear or deterioration from other causes, it becomes desirable to make replacement.

20. Removal of the entire switch assembly as a unit from the casing 10 is effected by first unscrewing the lever 22 and then detaching the lamp, which is adapted normally and while held in operative position in the casing to compress the contact members and thus keep them under constant tension.

25. The rim of the insulation block 21 is preferably sheathed by a metal ring 32, which slidably fits in the casing 10 and has a suitable opening through its wall registering

with a corresponding opening in the block 21 to receive the lower end of the lever 22.

During operating of the lamp 11 the lever 22 and switch block 21 are positioned as illustrated in Fig. 2, that is to say the contact spring 24 whose contact point 25 is always eccentric to the axis of the block 21 is arranged to contact with the exposed inner face of the terminal member 16. To open the circuit and extinguish the lamp the block 21 is rotated slightly on its axis by means of the lever 22, the slot 23 of the casing being adapted to limit the movements of the lever. This movement of the block causes the contact point 25 to move onto the insulation face of the block 21 and out of contact with the terminal member 16, thus breaking the circuit. To restore the circuit, the movement of the lever and switch portion is reversed.

It will be obvious that my invention is not restricted to the specific embodiment herein described and shown.

I claim:

1. A device of the class described comprising, in combination, a casing having means at one end to receive a lamp, a terminal support in the opposite end of the casing, a terminal carried by the terminal support for electrical connection with a source of energy and arranged eccentric to the axis of the casing, said terminal having a portion exposed within the casing, a rotatable switch portion within the casing for establishing and dis-establishing electrical connection between said terminal and the lamp and having its axis substantially coincident with the axis of the casing, and control means associated with the switch portion and operable exteriorly of the casing for rotating the switch portion in either of opposite directions, said switch portion including an insulation block and a spring metal strip in one piece formed to provide opposing side portions for self-supporting gripping engagement with said block and free end portions for tensional contact with the terminal and the lamp.

2. A device of the class described comprising, in combination, a casing open at one end to receive a lamp and closed at the opposite end, a terminal in the closed end of the casing arranged eccentric to the axis thereof, a rotatable switch portion within the casing and having its axis substantially coincident with the axis of the casing, control means operable exteriorly of the casing for rotating the switch portion in either of opposite directions, and means carried by and movable with the switch portion for providing electrical connection between the lamp and the terminal, including a spring contact member on each side of the switch portion and means for supporting said contact members in quick detachable gripping engagement with the body of the switch portion.

3. In a device of the class described, in combination, a casing open at one end for receiving and supporting a lamp and closed at the opposite end, a terminal in said closed end of the casing arranged eccentric to the axis thereof, a rotatable switch portion within the casing, and control means operable exteriorly of the casing for rotating the switch portion in either of opposite directions, said switch portion including an insulation block having a transverse channel in its periphery and a recess on at least one side, and means removably supported on said block for establishing and dis-establishing electrical connection between said terminal and a lamp and including a spring metal strip seated in said channel and having extended end portions arranged to make gripping engagement with opposite faces of said block, at least one of said end portions having a lateral extension member extending into said recess.

4. In a device of the class described, in combination, a casing open at one end to receive a lamp and closed at the opposite end, a terminal in the closed end of the casing arranged eccentric to the axis thereof, a rotatable switch portion within the casing having its axis substantially coincident with the axis of the casing and including an insulation contact carrier and self-supporting means mounted on the carrier for establishing and dis-establishing electrical connection between said terminal and a lamp, said means including a unitary spring metal structure adapted to be quickly slipped on and off the carrier and having oppositely arranged side portions for gripping the contact carrier.

5. In a device of the class described, in combination, a casing open at one end to receive a lamp and closed at the opposite end, a terminal in the closed end of the casing arranged eccentric to the axis thereof, a rotatable switch portion within the casing including an insulation block and means on the block for establishing and dis-establishing electrical connection between said terminal and the lamp, said means including a U-shaped structure having side portions arranged on opposite sides of said block and having end portions formed to provide spring contact members, one of said members being adapted to permanently engage the lamp and the other of said members being adapted to be moved by said block into and out of engagement with said terminal.

6. In a device of the class described, in combination, a casing open at one end to receive a lamp and closed at the opposite end, a terminal in the closed end of the casing arranged eccentric to the axis thereof, a rotatable switch portion within the casing having its axis substantially coincident with the axis of the casing and including an insulation block, switch control means operable exteriorly of the casing for rotating said block

in either of opposite directions, and tensional contact means in quick detachable gripping engagement with the block for establishing and dis-establishing electrical connection between said terminal and a lamp, said means including spring metal portions arranged on opposite sides of the block and connected together to form a unitary structure adapted to enclose the block, and auxiliary securing means therefor.

In testimony whereof, I have signed my name to this specification.

FREDERICK C. HERSEE.
